UNITED STATES PATENT OFFICE.

ORLAND V. SMITH, OF BRIDGEPORT, CONNECTICUT.

BANK DEPOSIT-BOOK.

1,308,532.

Specification of Letters Patent.

Patented July 1, 1919.

Application filed November 28, 1917. Serial No. 204,443.

To all whom it may concern:

Be it known that I, ORLAND V. SMITH, a citizen of the United States, residing at the city of Bridgeport, Fairfield county, Connecticut, have invented certain new and useful Improvements in Bank Deposit-Books; and I do declare the following to be a full, clear, and exact description of the invention, such as will enable others skilled 10 in the art to which it appertains to make and use the same.

This invention relates to certain new and useful improvements in a bank deposit book especially designed for savings accounts in 15 which definite sums or amounts are deposited periodically. These accounts are known as club accounts, being given such designations as Christmas club, weekly savings club and vacation club, and require duplicate 20 records one of which is kept by the banking institution and the other by the customer.

This invention has for its principal object to simplify the banking operations and steps 25 in these club accounts so as to assure a true and correct record with the least expenditure of labor.

The invention consists in a book having a 30 fixed leaf and a removable leaf in the nature of a card to be kept by the bank, the fixed leaf being carbon-coated on one side and bearing on the opposite side the amounts due 35 and paid, together with a validating space in which validating impressions are made as the amounts are paid. The card is also marked in like manner and placed against the carbonized face of the sheet so as to receive 40 a copy of the validating impression made upon the fixed leaf of the book.

In the drawing—

40 Figure 1 is a view of the book opened, with the bank card in position to receive a validating impression;

Fig. 2 is a transverse section on line 2—2 of Fig. 1;

45 Fig. 3 is a fragmentary view of the book closed; and

Figs. 4 and 5 are obverse and reverse views of the card *per se*.

In its preferred embodiment, the book 50 comprises a cover 1 and a double sheet 2 secured by stitching 3 on a central line of fold so as to provide front and back covers and a filler of two leaves. Each leaf has its side next to the cover coated with carbon 4 and its opposite face ruled transversely and vertically to provide five columns. In column 5

are numerals indicating the weeks, starting with 1 and running consecutively throughout the number of weeks over which the club is extended, in this instance being 50. The 60 second column 6 bears the weekly amounts due while column 7 contains the total sum paid to date. For convenience and also to facilitate matters, column 8 is provided for containing predetermined multiples of the 65 weekly payment which multiples occur opposite the corresponding figures in column 7. Column 9 is the validating column, containing blank spaces which are to be initialed or otherwise impressed by the receiving teller 70 of the bank upon receipt of a corresponding payment.

This book is designed to be kept by the customer who is to present it when each payment is made. The bank's record 75 consists of a card 10 which is more in the nature of a removable sheet of the book, the same being insertible beneath the leaf between the latter and the cover, or, in other words, in contact with the carbon facing, to receive 80 a copy of the validating impression made upon the leaf of the customer's book. This card need not be ruled horizontally but the vertical columns are to bear indications practically identical with the markings on 85 the leaf so that a true and perfect registry may be accomplished when the card and leaf are relatively superposed.

The card is preferably reversible having 90 columns and indications on its reverse side corresponding to those on the second leaf of the book. Consequently, only one card is requisite for a two-leaf book.

The book is given a class number 11 and 95 serial number 12 which numbers should agree with those on the card or bank's record, in which connection it will be noted that the serial number on the card will be exposed to view, when the card is positioned beneath the leaf, in proximity to that of the book so that easy comparison may be obtained. The name of the customer may be written on line 13 on the card for ready reference, and a tab 14, either with or without an identifying marking for guidance in 100 assorting the cards in a drawer, may also be provided.

In practice, say the customer makes his initial deposit, the receiving teller locates the card in his card drawer, and inserts it 110 beneath the first leaf of the book so as to have the columns properly register. He

then initials the validating space in line with the first week, as in Fig. 1, which, by reason of the interposed carbon layer, is reproduced on the card which latter the teller 5 then removes and replaces in his card drawer or file, returning the book to the customer.

Thus a true and correct record of all payments made and due is kept with the least 10 amount of labor and inconvenience. A separate sheet of carbon does not have to be inserted and when all the payments are made on one side of the book, the card is reversed and inserted beneath the opposite 15 page. Further, a complete record of all the payments made and to whom made or by whom received is always at hand.

What is claimed is:

1. In combination with a depositor's bank 20 book consisting of a foldable cover and a sheet secured to the cover along the line of fold and having a carbon surface on its side opposing the cover, the opposite side of the sheet being divided by the line of fold into 25 two pages each containing data relating to predetermined payments and validating

spaces opposite the same, a reversible bank record card having similar prepayment data and validating spaces on each side corresponding respectively to that on the two 30 pages, said card insertible beneath the opposite pages between the carbon surface and the cover.

2. In combination with a depositor's bank book consisting of a cover and a filler of 35 four pages, the first and last pages having a carbon surface and the intermediate pages each containing data relative to successive time periods and validating spaces opposite the same, means securing the filler to the 40 cover, and a reversible bank record card bearing similar data and spaces on both sides corresponding to the data and spaces on the respective intermediate pages and registerable therewith upon insertion beneath the respective carbon surfaces, said filler-securing means providing a common stop 45 for the inner edge of the card when inserted from either side.

In testimony whereof I affix my signature. 50

ORLAND V. SMITH.
